ATTORNEY

UNITED STATES PATENT OFFICE.

MORITZ KIRCHBERGER, OF NEW YORK, N. Y.

DESIGN FOR A LAMP-SHADE.

SPECIFICATION forming part of Design No. 20,853, dated June 23, 1891.

Application filed May 8, 1891. Serial No. 392,104. Term of patent 7 years.

To all whom it may concern:

Be it known that I, MORITZ KIRCHBERGER, a citizen of the United States, residing at New York city, in the county and State of New York, have invented and produced a new and original Design for Lamp Shades or Globes, of which the following is a specification, reference being had to the accompanying drawing, forming part thereof, which represents a side 5 elevation of a globe or shade embodying the features of my design.

The essential feature of the design consists in the lower and intermediate portions of a lamp globe or shade body, which present nine 10 closely-grouped flat-surfaced figures. The above effect is obtained by a grouping of

spaced vertically-disposed curved ribs A, commencing at the bottom of the body and losing themselves in a plain convexed surface B at the upper portion of the body. The spaces C 20 between the ribs appear flat at their upper portions and gradually taper off in the plain convexed surface B, while the lower marginal portions of the spaces are somewhat dished.

I claim—

The design for a lamp shade or globe herein shown and described.

MORITZ KIRCHBERGER.
